MAGNETIC-SUCTION SOAP HOLDER

Charles H. Hagopian, 2344 Davidson Ave.,
Bronx, N.Y. 10068

Original design application May 28, 1969, Ser. No. 17,403,
now Patent No. 218,330, dated Aug. 11, 1970. Divided
and this application May 4, 1970, Ser. No. 22,803

Term of patent 14 years

Int. Cl. D6—01

U.S. Cl. D33—25

FIG. 1

FIG. 2

FIG. 3

FIG. 1 is a rear elevational view of a magnetic suction soap holder showing my new design;

FIG. 2 is a front perspective view thereof; and

FIG. 3 is a top plan view thereof.

This is a division of design application Ser. No. D. 17,403, filed May 28, 1969, now Design Pat. No. D. 218,330, issued Aug. 11, 1970.

I claim:

The ornamental design for a magnetic suction soap holder, substantially as shown and described.
